Primary Examiner — Susan Bennett Hattan*Assistant Examiner* — Marie D. Fast Horse(74) *Attorney, Agent, or Firm* — Egbert Law Offices, PLLC(57) **CLAIM**

The ornamental design for a telecommunications apparatus, as shown and described.

DESCRIPTION

FIG. 1 is a first side perspective view of a telecommunications apparatus showing my new design.

FIG. 2 is a second side perspective view thereof;

FIG. 3 is a top view thereof;

FIG. 4 is a front view thereof;

FIG. 5 is a rear view thereof; and,

FIG. 6 is a side view thereof, an opposite side view being a mirror image thereof.

The bottom surface of the telecommunications apparatus is flat, devoid of surface ornamentation, and forms no part of the claimed design. The features presented in broken lines represent unclaimed portions of the telecommunications apparatus and form no part of the claimed design.
